CLOTHES DRYING MACHINE

Clifford E. Erickson, Chicago, Ill., assignor to
General Electric Company, a corporation of
New York

Application March 30, 1951, Serial No. 218,427

3 Claims. (Cl. 34—139)

1

The present invention relates to clothes drying machines of the portable home laundry type and more particularly to improved clothes drying machines of the general character disclosed in the copending application of Kemper M. Hammell and Clifford E. Erickson, Serial No. 75,606, filed February 10, 1949.

The clothes drying machine disclosed in the Hammell and Erickson application mentioned is of the portable home laundry type and comprises a cabinet housing a casing, that, in turn, encloses a clothes receiving drum; the cabinet is provided with an upstanding front wall having an access opening formed therein; the casing is provided with an upstanding front wall having an access opening formed therein; and the drum is provided with an upstanding front wall having an access opening formed therein. The front access openings are arranged in substantial alignment and the cabinet front wall carries a front door mounted for movements between open and closed positions with respect to the front access openings. The drum is mounted for rotation about its longitudinal axis disposed in a substantially horizontal position and substantially normal to the cabinet front wall. The drum is also provided with a substantially cylindrical perforated side wall; and the casing is also provided with a substantially tubular side wall that cooperates with the drum side wall to define first and second chambers therebetween respectively disposed adjacent to the top of the drum and adjacent to the bottom of the drum. An electric motor is provided for rotating the drum in order to tumble the contained clothes and for producing circulation of a current of air from the first chamber through the drum into contact with the contained clothes and thence into the second chamber and back into the first chamber. An electric heating element is arranged in the first chamber in order to heat the current of air passing therethrough; and a spray nozzle is arranged in the second chamber in order to cool and to scrub with a finely divided spray of cool water the current of air passing therethrough. A sump is formed in the bottom of the casing below the second chamber in order to accumulate the water, as well as condensate and lint scrubbed from the current of air as it is passed through the second chamber. A drain opening is formed in the bottom of the sump; and a pump is provided that communicates between the drain opening and the exterior, the pump being operated by the motor for the purpose of discharging to the exterior the water and the condensate and the lint accumulating in the

2

sump. Further an inlet conduit is provided that is supplied with cool water under gauge pressure from the city water main; and a plumbing connection is arranged between the inlet conduit and the spray nozzle, the plumbing connection including a solenoid controlled valve that is selectively operative between closed and open positions in order selectively to govern the supply of the cool water from the inlet conduit to the spray nozzle.

Finally in this machine, a first sealing arrangement is provided between the cabinet front wall and the casing front wall in surrounding relation with respect to the front access openings respectively formed therein in view of the fact that it is necessary to seal the space between the cabinet front wall and the casing front wall against the entry thereinto of hot air from the drum; and a second sealing arrangement is provided between the cabinet front wall and the front door in surrounding relation with respect to the front access opening formed in the cabinet front wall in view of the fact that it is necessary to seal the front openings against the passage of hot air from the drum to the exterior.

While the sealing arrangements noted above that are provided in this machine are quite satisfactory, they are considerably more expensive to manufacture than are desirable in the interest of economy.

Accordingly it is a general object of the present invention to provide in a clothes drying machine of the character described, improved and simplified sealing arrangements respectively between the cabinet front wall and the casing front wall and between the cabinet front wall and the associated front door.

It is another object of the invention to provide in a clothes drying machine of the character described, an improved entry throat and gasket member that is operatively associated with the front openings thereof, which member not only provides the two seals previously noted but also terminates in a rearwardly directed and outwardly flared lip projecting into the front opening formed in the drum front wall to provide a smooth throat from the exterior into the interior of the drum through the front openings noted.

Further features of the invention pertain to the particular arrangement of the elements of the throat and gasket member and of the clothes drying machine, whereby the above-outlined and additional operating features thereof are attained.

The invention, both as to its organization and method of operation, together with further ob-

3

jects and advantages thereof, will best be understood by reference to the following specification taken in connection with the accompanying drawings, in which Figure 1 is a front perspective view of a clothes drying machine of the portable home laundry type incorporating an entry throat and gasket arrangement embodying the present invention; Fig. 2 is a longitudinal sectional view, partly broken away, of the machine, taken in the direction of the arrows along the offset line 2—2 in Fig. 1; Fig. 3 is a rear elevational view, partly broken away, of the machine; and Fig. 4 is an enlarged fragmentary sectional view of the front portion of the machine, taken in the direction of the arrows along the line 4—4 in Fig. 1, and illustrating the construction of the entry throat and gasket member.

Referring now to Figs. 1 to 3, inclusive, of the drawings, the clothes drying machine 10 there illustrated is of the portable home laundry type and is of the general character of that disclosed in the previously-mentioned Hammell and Erickson application, and incorporated an entry throat and gasket arrangement embodying the features of the present invention. Specifically the machine 10 is of the improved construction and arrangement of that disclosed and claimed in the copending application of Clifford E. Erickson and Glenn D. Graham, Serial No. 209,657, filed February 6, 1951, and comprises a substantially rectangular base 11 carrying an upstanding detachable cabinet 12; the cabinet 12 includes a front wall 13, and a pair of opposed side walls 14 and 15 defining both a rear opening and a top opening. The rear opening provided in the cabinet 12 is closed by a removable rear wall 16; and the top opening provided in the cabinet 12 is closed by a removable top wall 17. The front wall 13 is provided with a rearwardly directed rim or boundary flange 18 having side portions disposed substantially flush with the side walls 14 and 15, and a bottom portion disposed forwardly of the front of the base 11 and cooperating therewith to define an upstanding toe-receiving recess 19 arranged at the lower front of the cabinet 12. Also the central portion of the front wall 13 has a substantially rectangular depression 20 formed therein that is surrounded by a rearwardly directed boundary throat 21. Preferably the front wall 13 is formed of one-piece die-pressed construction and carries a substantially rectangular fabricated front door 22 suitably hinged thereto and arranged within the boundary throat 21 and movable between open and closed positions with respect to the depression 20, the front door 22 carrying a suitable handle and latch mechanism 23.

The top wall 17 includes a substantially horizontally disposed work surface 24 provided with a downwardly turned rim or boundary flange 25 that includes front and side portions disposed substantially flush with the upper portions of the respective front wall 13 and side walls 14 and 15. Also the rear portion of the top wall 17 terminates in a laterally extending and upwardly directed backsplash 26 that projects rearwardly of the rear wall 16 to define an upstanding space 27 disposed both below the backsplash 26 and behind the rear wall 16 and employed for a purpose more fully explained hereinafter. The side portions of the rim 25 of the top wall 17 merge into the ends of the backsplash 26 to form a smooth continuous construction. Preferably the hollow top wall 17 is formed of one-piece die-pressed construction. A timer switch, not shown,

is housed within the hollow backsplash 26 adjacent to the right-hand end thereof and provided with an operating shaft extending through an opening formed therein and carrying a manual control dial 28 that is readily accessible from the exterior; and a thermostatic switch 29 is housed within the hollow backsplash 26 adjacent to the left-hand end thereof and provided with an operating shaft extending through an opening formed therein and carrying a manual control dial 30 that is readily accessible from the exterior. Finally the central portion of the backsplash 26 carries a combination ornamental trim and lamp hood 31 that is adapted to be illuminated by an electric lamp, not shown, housed in the backsplash 26 for the purpose of indicating operation of the machine 10, and of providing some illumination of the work surface 24 of the top wall 17.

An upstanding substantially tubular casing 32 is housed in the front portion of the cabinet 12 and provided with front and rear walls 33 and 34 and a tubular side wall 35, the casing 32 being supported upon the base 11 by an arrangement including two upstanding and laterally spaced-apart pillars 36 and 37. A substantially cylindrical drum 38 is enclosed by the casing 32 and provided with front and rear walls 39 and 40 and a perforated side wall 41. The drum 38 is mounted for rotation in the casing 32 about its longitudinal axis disposed in a substantially horizontal position substantially normal to the casing front wall 33 by an arrangement including a spider 42 secured to the rear surface of the drum rear wall 40 and carrying a rearwardly projecting drive shaft 43. The drive shaft 43 is disposed along the longitudinal center line of the drum 38 and projects through an opening provided in the casing rear wall 34 into an upstanding space 44 defined between the casing rear wall 34 and the cabinet rear wall 16. The drive shaft 43 is supported for rotation in bearing structure carried by a bolster 45, that is, in turn, carried by the casing rear wall 34 and arranged in the upstanding space 44.

The upper portion of the tubular side wall 35 of the casing 32 cooperates with the associated cylindrical side wall of the drum 38 to define a longitudinally extending first or heating chamber 46 therebetween disposed adjacent to the top of the drum 38, in which there are arranged a pair of elongated electric heating elements 47, preferably of the sheathed resistance conductor type, the heating elements 47 being directly supported by the rear wall 34 of the casing 32. Arranged between the heating elements 47 and the adjacent portion of the tubular side wall 35 of the casing 32 is a longitudinally extending and substantially arcuate-shaped reflector 48 that is provided for the purpose of reflecting radiant heat toward the perforated cylindrical side wall 41 of the drum 38. The lower portion of the tubular side wall 35 of the casing 32 cooperates with the associated cylindrical side wall 41 of the drum 38 to define a longitudinally extending second or condensing chamber 49 therebetween disposed adjacent to the bottom of the drum 38. Also the lower portion of the tubular side wall 35 of the casing 32 comprises a downwardly extending or dished wall defining a sump 50 in the bottom thereof, the sump 50 being disposed below the condensing chamber 49 and constitutes the bottom thereof. The top of the condensing chamber 49 is defined by a longitudinally extending and generally arcuate-shaped baffle 51

that is arranged just below the bottom of the cylindrical side wall 41 of the drum 38. As best shown in Fig. 3 and as viewed from the rear of the cabinet 12, the lower right-hand side of the tubular side wall 35 of the casing 32 extends downwardly and away from the adjacent portion of the cylindrical side wall 41 of the drum 38 in order to provide a scroll-shaped section that cooperates with the adjacent portion of the cylindrical side wall 41 of the drum 38 to define a compression chamber 52 therebetween that opens into the adjacent end of the condensing chamber 49 below the baffle 51; and the lower left-hand side of the tubular side wall 35 of the casing 32 extends upwardly and toward the adjacent portion of the cylindrical side wall 41 of the drum 38 in order to provide therebetween an arcuate-shaped passage 53 communicating between the adjacent open end of the condensing chamber 49 and the adjacent open end of the heating chamber 46. The drum 38 is rotated in the clockwise direction, as viewed from the rear of the machine 10 in Fig. 3, whereby the clothes contained therein are tumbled and a circulation of a current of air is produced from the heating chamber 46 into the drum 38 through the perforated cylindrical side wall 41 thereof and into contact with the contained clothes. The air current is then circulated from the drum 38 through the perforated cylindrical side-wall 41 thereof into the compression chamber 52, wherein the air is compressed and forced into the adjacent end of the condensing chamber 49. The air passes through the condensing chamber 49 between the sump 50 and the baffle 51 and thence out of the other end thereof and through the passage 53 and again into the heating chamber 46. This forced circulation of the current of air is produced solely by the rotation of the drum 38 in the clockwise direction, as viewed in Fig. 3, at a speed of approximately 50 R. P. M., together with the tumbling of the clothes contained in the drum 38, all without the usual external blower or fan.

Also the machine 10 comprises an electric drive motor 54 pivotally mounted upon the pillar 37, and a drive arrangement including a floating stub shaft 55, a series of pulleys 56, 57, 58 and 59 and two flexible belts 60 and 61 so as to provide a speed reduction arrangement between the shaft of the motor 54 and the drive shaft 43, the pulleys 56, etc., and the belt 60, etc., being arranged in the space 44. Further the machine 10 comprises a cooling water supply system including an inlet conduit 62 that is adapted to be supplied with cool water under gauge pressure, the rear end of the inlet conduit 62 being provided with a threaded nipple 62' that is adapted detachably to receive a flexible rubber cool water supply hose, not shown, arranged in the upstanding space 27 and extending through an opening, not shown, formed in the cabinet rear wall 16. The front end of the inlet conduit 62 communicates with a fixture 63, that, in turn, communicates with a valve 64 of the solenoid control type and provided with a solenoid 65. The valve 64 is normally biased into its closed position and is operated into its open position in response to energization of the solenoid 65. The upper portion of the valve 64 communicates with a vacuum breaker 66, that, in turn, communicates with a flow control regulator 67. Preferably the flow control regulator 67 is of the flexible diaphragm compression aperture or throat-type that is designed to maintain a substantially

constant flow of cool water therethrough when the valve 64 occupies its open position, notwithstanding considerable variation of the gauge pressure of the cool water supplied to the inlet conduit 62. For example, the flow control regulator 67 may be designed to maintain a substantially constant flow of approximately 0.4 gallon per minute of cool water therethrough. Finally the flow control regulator 67 communicates with a tube 68 that terminates in two spray nozzles 69 arranged in the lower portion of the condensing chamber 49.

More particularly the longitudinal extending generally arcuate-shaped baffle 51 is arranged immediately below the bottom of the cylindrical side wall 41 of the drum 38; and a longitudinally extending arcuate-shaped baffle 70 is arranged in spaced relation below the baffle 51 and above the bottom wall of the sump 50 and joining the right-hand portion of the tubular wall 35 of the casing 32, as viewed in Fig. 3. Thus the condensing chamber 49 has a generally arcuate shape and is disposed between the baffles 51 and 70. The spray nozzles 69 are arranged substantially centrally of the lower portion of the casing 32 adjacent to the end of the baffle 70. More specifically the spray nozzles 69 are disposed in circumferentially spaced-apart relation and are directed upwardly at an angle toward the baffle 51, whereby the spray nozzles 69 project a finely divided spray of cool water upwardly at an angle between the baffles 51 and 70 when the valve 64 occupies its open position. Since the spray nozzles 69 are directed upwardly at an angle with respect to the baffle 51, a component of the direction of the spray of cool water is in counterflow relation with respect to the direction of circulation of the current of air through the condensing chamber 49, so as to effect a thorough scrubbing of the current of air as it is passed therethrough.

The bottom of the sump 50 has a drain opening formed in the lower portion thereof that receives the adjacent end of a drain conduit 71 formed of rubber, or the like, the rear end of the drain conduit 71 communicating with a pump 72 mounted on the base 11 and driven from the motor 54 by an arrangement including a belt 73 and associated pulleys. The casing of the pump 72 is provided with a discharge port 74, that, in turn, communicates with a flexible rubber drain hose, not shown, that also projects through the opening, not shown, provided in the cabinet rear wall 16 into the upstanding space 27.

In view of the foregoing, it will be understood that the upwardly directed spray of finely divided cool water from the spray nozzles 69 effects the condensation of moisture from the current of air circulated through the condensing chamber 49, as well as the scrubbing of lint therefrom, whereby the water, the condensate and the lint accumulating in the sump 50 is removed to the exterior of the casing 32 by operation of the drain pump 72.

Further the machine 10 comprises an electric control circuit network as disclosed in the previously-mentioned Erickson and Graham application, whereby it may be operated automatically through a timed cycle. Also as indicated in Fig. 3, the cylindrical side wall 41 of the drum 38 comprises three substantially equally circumferentially spaced-apart longitudinally extending and inwardly projecting vanes 74 that effect tumbling of the clothes contained in the drum 38 and assist in the production of the circulation of the cur-

rent of air through the drum 38 and within the casing 32, in the manner explained above.

Referring now more particularly to Figs. 2 and 4 of the drawings, the boundary throat 21 surrounding the rectangular depression 20 formed in the cabinet front wall 13 is provided with rearwardly and inwardly extending portions 21a and 21b, respectively, the inwardly extending portion 21b terminating in an annular access opening 75 arranged rearwardly of the front door 22 and 10 inwardly with respect to the portion 21a. Also the front wall 33 of the casing 32 has a substantially annular access opening 76 formed therein that is surrounded by an associated annular stiffening ridge 77; and the front wall 39 15 of the drum 38 is provided with a centrally disposed and forwardly flared annular flange 78 terminating in an annular access opening 79. The annular access openings 75, 76, and 79 are arranged in longitudinal alignment with each other along the longitudinal center line of the drum 38 and cooperate with an annular entry throat and gasket member 80; preferably the member 80 is of one-piece extruded construction, although it may be molded, and is formed of 20 flexible and deformable rubber, or the like. More particularly the member 80 includes an annular sleeve-like body 81 bridging the space between the portion 21b of the boundary throat 21 and the casing front wall 33 and terminating in a rearwardly directed and outwardly flared lip 82 bridging the space between the casing front wall 33 and the drum front wall 39 and projecting into the drum 38 through and out of contact with the front access opening 79 so as to provide a smooth access throat from the exterior through the front access openings 75, 76, and 79 into the interior of the drum 38 when the front door 22 occupies its open position. The body 81 of the member 80 also has a surrounding substantially annular slot 83 formed therein that receives and embraces the sides of the portion 21b of the boundary throat 21 so as to retain the member 80 in place. The intermediate portion of the body 81 carries a first substantially annular hollow deformable gasket section 84 arranged between the portion 21b of the boundary throat 21 and the stiffening ridge 77 provided on the casing front wall 33. The first gasket section 84 is arranged between the parts noted and in surrounding relation with respect to the front access openings 75 and 76 so as to seal together the cabinet front wall 13 and the casing front wall 33. The front portion of the body 81 carries a second substantially annular hollow deformable gasket section 85 arranged between the portion 21b of the boundary throat 21 and the inner surface of the front door 22, the second gasket section 85 being disposed in the depression 20 adjacent to and in surrounding relation with the front access opening 75 formed in the cabinet front wall 13. When the front door 22 occupies its closed position, the second gasket section 85 is compressed between the inner surface of the front door 22 and the portion 21b of the boundary throat 21 so as to seal the front access opening 75 against the escape of hot air from the interior of the drum 38 into the depression 20 formed in the cabinet front wall 13.

In making the member 80, an appropriate length of the preformed extruded or molded stock is cut therefrom, and the adjacent ends thereof are vulcanized or cemented together to provide the annular ring-like form. Thereafter the member 80 is appropriately deformed and applied

5 to the portion 21b of the boundary throat 21 and to the casing front wall 33 in its position illustrated in Fig. 4. Due to the resiliency of the member 80, it will be appreciated that it may be conveniently removed and replaced by a repairman in the event this is necessary.

Also as illustrated in Fig. 4, the front door 22 is of hollow fabricated construction, the interior thereof including a supporting element 86 that is employed for the purpose of pivotally mounting the front door 22 upon the adjacent portion 21a of the boundary throat 21, the arrangement employing upper and lower concealed hinges, the lower concealed hinge being illustrated at 87. Specifically the lower hinge 87 comprises first and second leaves 88 and 89 pivoted together by an associated pintle 90, the hinge 87 being arranged primarily within the hollow front wall 13 exteriorly of the boundary throat 21. More particularly the leaf 88 is suitably secured to the exterior surface of the portion 21a of the boundary throat 21; while the leaf 89 is curved and extends through an elongated slot 91 formed in the boundary throat 21 adjacent to the junction between the portions 21a and 21b thereof, the outer end of the leaf 89 extending through an opening into the interior of the front door 22 and being secured to the supporting element 86 by an arrangement including a threaded member 92 and a cooperating nut 93.

From the foregoing, it will be understood that the front door 22 is readily pivotally mounted between its open and closed positions upon the hinges 87, etc., described above, whereby the interior of the drum 38 is readily accessible from the exterior through the member 80 when the front door 22 occupies its open position. On the other hand, when the front door 22 occupies its closed position, the second gasket section 85 of the member 80 provides a seal about the front access opening 75 preventing the escape of hot air from the interior of the drum 38 into the depression 20 formed in the cabinet front wall 13. Further when the front door 22 occupies its closed position, the front or outer face thereof 45 is disposed substantially flush with the cabinet front wall 13 in order to provide a smooth and finished appearance to the cabinet 12. The member 80 not only provides a smooth throat from the exterior into the interior of the drum 38. 50 Further when the front door 22 occupies its closed position, the front or outer face thereof 45 is disposed substantially flush with the cabinet front wall 13 in order to provide a smooth and finished appearance to the cabinet 12. The member 80 not only provides a smooth throat from the exterior into the interior of the drum 38. 55 preventing the clothes from being caught upon the edge of the flared annular flange 78 incident to the introduction of the clothes into the drum 38, but the lip 82 also provides a barrier preventing any possibility of the clothes working between the drum front wall 39 and the casing front wall 33 during rotation of the drum 38. The second gasket section 85 not only seals the front access opening 75 provided in the boundary throat 21, but it cooperates with the first gasket section 84 in order to seal the space between the casing front wall 33 and the cabinet front wall 13, as it is highly undesirable for the moisture or vapor in the sump 50 formed in the bottom of the casing 32 from rising and entering 60 between the casing front wall 33 and the cabinet front wall 13 since the presence of such vapor in the space noted would lead to condensation therein due to the fact that the cabinet front wall 13 is at a lower temperature than the casing front wall 33.

In view of the foregoing, it is apparent that there has been provided in a clothes drying machine of the portable home laundry type including a closed air circulating system involving a

heating chamber and a spaced-apart spray condensing chamber, an improved throat and sealing arrangement for the front access openings respectively provided in the cabinet front wall, the casing front wall, and the drum front wall.

While there has been described what is at present considered to be the preferred embodiment of the invention, it will be understood that various modifications may be made therein, and it is intended to cover in the appended claims all such modifications as fall within the true spirit and scope of the invention.

What is claimed is:

1. In a clothes drying machine of the class described including a cabinet having an upstanding front wall provided with a front access opening formed therein, a casing housed in said cabinet and having an upstanding front wall provided with a front access opening formed therein, a substantially horizontally disposed clothes-receiving drum enclosed in said casing and having a substantially cylindrical perforated wall and an upstanding front wall provided with a front access opening formed therein, said casing front wall being arranged adjacent to and in spaced relation with both said cabinet front wall and said drum front wall, said front access openings being substantially annular and arranged substantially in alignment with each other, said cabinet front wall having a rearwardly directed depression formed therein and surrounding said front access opening formed therein, a front door carried by said cabinet front wall and mounted in said depression for movements between closed and open positions with respect to said front access openings, said front door being provided with inner and outer walls arranged in spaced-apart relation, said inner wall being spaced forwardly of the portion of said cabinet front wall disposed within said depression and said outer wall being disposed substantially flush with the portion of said cabinet front wall surrounding said depression when said front door occupies its closed position, said drum front wall having a forwardly flared annular rim surrounding said front access opening formed therein and spaced rearwardly from said casing front wall, and means for rotating said drum about its longitudinal axis; the combination comprising a unitary throat member including an annular sleeve-like body bridging the space between the portion of said cabinet front wall disposed in said depression and said casing front wall and termi-

nating in a rearwardly directed and outwardly flared lip bridging the space between said casing front wall and said drum front wall and projecting into said drum through said front access opening formed therein in order to provide a smooth access throat from the exterior through said front access openings into the interior of said drum, said sleeve-like body having a surrounding annular slot formed therein and embracing the sides of the portion of said cabinet front wall disposed in said depression in order frictionally to secure said member in place, the intermediate portion of said sleeve-like body carrying a first hollow deformable gasket arranged in compression between the portion of said cabinet front wall disposed in said depression and said casing front wall adjacent to and in surrounding relation with said front access openings respectively formed therein and sealing the space therebetween, the front portion of said sleeve-like body carrying a second hollow deformable gasket arranged in said depression adjacent to the portion of said cabinet front wall disposed in said depression and in surrounding relation with said front access opening formed therein, said second gasket being compressed between the portion of said cabinet front wall disposed in said depression and said inner wall and sealing the space therebetween when said front door occupies its closed position.

2. The clothes drying machine combination set forth in claim 1, wherein said sleeve-like body and said first and second hollow gaskets are of one-piece construction formed of flexible and deformable material.

3. The clothes drying machine combination set forth in claim 2, wherein said one-piece construction is continuous about said front openings.

CLIFFORD E. ERICKSON.
